UNITED STATES PATENT OFFICE.

HANSON B. JOYCE, OF SEATTLE, WASHINGTON.

SHOW-CASE.

No. 927,052.

Specification of Letters Patent.

Patented July 6, 1909.

Application filed February 23, 1906. Serial No. 302,599.

To all whom it may concern:

Be it known that I, HANSON B. JOYCE, a citizen of the United States of America, and a resident of the city of Seattle, in the county of King and State of Washington, have invented certain new and useful Improvements in Show-Cases, of which the following is a specification.

The primary object of my invention is to 10 provide a simplified and improved show-case which is capable of being readily converted into a refrigerating-chamber to meet varying temperatures in displaying perishable goods.

With the above, and other desirable objects referred to hereinafter in view, my invention resides in the construction, combination and arrangement of parts as set forth in this specification and defined in the appended claims.

20 With reference to the accompanying drawing, in which similar reference numerals designate corresponding parts throughout, Figure 1 is a plan view of my improved show-case in partial section taken on line 1 of Fig. 25 2 showing the same with the parts assembled to provide a refrigerating-chamber. Fig. 2 is a side view in partial section on line 2 of Fig. 1. Fig. 3 is a transverse section on line 3-3 of Fig. 2, and Fig. 4 is a view in perspective of the removable top-wall section shown with a portion thereof broken away.

In carrying out my invention I provide a main frame comprising a bottom 2, corner posts 3 secured thereon, and side and end 35 rails 4, 4 and 5, 5 respectively which are fastened to said posts. Intermediate the end rails 5 are cross-pieces 6 which are suitably spaced apart and secured to the side-rails.

40 Reference numeral 7 indicates a frame of suitable size to fit in the space between cross-pieces 6, and when so placed engaging in suitable rabbets provided in said pieces and the intervening portions of the side-rails 4 so 45 that it can be readily removed, and 8, 8 indicates similar frames fitting between said cross-pieces and the end-rails 5 and engaging in suitable rabbets provided in said pieces and the end and side rails of the main frame.

50 The frames 7 and 8, 8, are provided with panels, as 7' and 8' respectively, consisting of sections of glass or other suitable transparent material, secured in suitable rabbets provided in the members of respective frames, and said frames are preferably 55 swingably connected with adjacent end-rails

5 by suitable hinges so that they may be raised to give access to the case. The sides and ends of the main frame are provided with walls of transparent material as sections 60 of glass 9, 9 and 10, 10 respectively which are secured in rabbets provided in the adjacent members of said frame.

Reference numerals 9', 9' and 10', 10' indicate supplemental wall sections consisting of 65 sections of glass or other suitable material removably secured in opposing relations to the main side and end walls 9, 9 and 10, 10 respectively but are spaced therefrom to provide air chambers between said main walls 70 and their respective supplemental sections.

The supplemental wall sections 9' and 10' are mounted in suitable frames 9" and 10" respectively, the latter of which are preferably of suitable length to overlap the adjacent end-rails of the former when said sections are in place. These frames are provided on their inner side faces with strips of suitable packing, as p, which have contact with adjacent members of the main frame, 75 80 and the supplemental frames are conveniently secured in place by screws 12 passing therethrough and engaging the main frame. Furthermore, if desired, the end rails of the frames 9" may be secured to the adjacent 85 corresponding rail of frames 10" by suitable means, as screws 12', whereby, when the screws 12 are removed all of the supplemental walls can be removed simultaneously as a unit, by slipping them upwardly from the 90 main frame.

14 designates a casing inclosing a chamber for ice and provided with a suitable aperture in the top wall normally closed by a cover 15 which is suitably hinged to said casing so 95 that it may be opened when desired to have access to the chamber. The casing 14 is provided with a lateral projection, as a flange 16, extending about its margin adjacent the top and engaging in the rabbet of the cross-pieces 6 and intervening portions of the side-rails 4 of the main frame, whereby the said casing, when in place, serves as a closure for the space between said cross-pieces and extends into the interior of the show-case for 100 105 the purpose of refrigeration.

In the bottom portion of the show-case I have shown a water-chamber 17 conveniently consisting of tubing arranged in the form of a coil which is connected with a suitable discharge valve 18 located exterior to the show-case and also with casing 14. The 110 115

latter connection consisting of a flexible tubing 19 connected with a suitable aperture provided in the bottom of said casing and detachably engaged with a nipple or the like on said coil. Thus the drippings from the ice in casing 14 will pass to said water chamber and may be retained therein, by closing valve 18, as a cooling agent.

From the foregoing it will be readily understood that the wall section 7 can be readily substituted for casing 14 and the supplemental wall sections removed when the weather is cool, and said casing and wall sections replaced to convert the show-case into a refrigerating-chamber when the weather is warm.

Having thus described my invention, what I claim as new, and desire to secure by Letters Patent of the United States of America,

20 is:—

1. A show case comprising a main frame consisting of a bottom, corner posts secured thereto, side and end rails secured to said corner posts, said rails being formed with 25 rabbets, and transparent panels engaged in the rabbets of said rails, and a casing comprising side and end walls consisting of a frame secured to said rails, and transparent panels in said frame spaced from said main 30 frame panels.

2. A show case comprising a main frame having its side and end walls of transparent

material, rails in which said walls are secured projecting outwardly beyond the same, and supplemental side and end wall sections comprising frames secured to the said rails and having glass panels therein spaced from the side and end walls of said main frame.

3. A show case comprising a main frame and supplemental end and side walls spaced therefrom, said supplemental side and end walls being removably connected, and means removably securing the same to said main frame, whereby they can be removed as a unit from said main frame.

4. A show case comprising a main frame consisting of end and side walls of transparent material, supplemental side and end walls removably secured to the end and side walls of said frame and spaced therefrom, means removably securing said supplemental side and end walls together, means removably securing the same to said main frame, whereby they can be removed therefrom as a unit, and packing arranged between said supplemental 55 end and side walls and the adjacent walls of said main frame.

Signed at Seattle, Washington this 13 day of February 1906.

HANSON B. JOYCE.
